UNITED STATES PATENT OFFICE.

FRANCIS E. FOULKE, OF PHILADELPHIA, PENNSYLVANIA, ASSIGNOR TO MAXIMUM MOTORS CO. INC., OF NEW YORK, N. Y., A CORPORATION OF NEW YORK.

INTERNAL-COMBUSTION ENGINE.

Application filed March 28, 1918. Serial No. 225,392.

To all whom it may concern:

Be it known that I, FRANCIS E. FOULKE, a citizen of the United States of America, residing at Philadelphia, in the county of Philadelphia and State of Pennsylvania, have invented certain new and useful Improvements in Internal-Combustion Engines, of which the following is a specification, reference being had therein to the accompanying drawings.

The invention relates to internal combustion engines of the rotary valve type. In the usual arrangement of internal combustion engine the induction manifold extends the length of the engine and is adapted to communicate with the cylinders of the engine by means of valve controlled passages. This arrangement is objectionable because the valves do not operate consecutively so that the gases in the manifold surge back and forth and are not evenly distributed whereby the same amounts of gases do not enter each of the cylinders. Applicant has overcome these objections by an arrangement in which the gases are permitted to enter at opposite ends of the engine so that the amount of surging is greatly decreased and the gases are more evenly distributed. Another object of the invention is to obtain a construction in which the gases passing through the induction conduit are heated before entering the cylinders. Still another object of the invention is to obtain a simple efficient construction in which the rotary valves are accurately driven. Further objects of the invention reside in the novel arrangements and combinations of parts as more fully hereinafter described.

In the drawings:
Figure 1 is a sectional elevation of the engine;

Figure 2 is a transverse section thereof on the line 2—2 of Figure 3.

Figure 3 is a sectional elevation of a modified construction.

Figure 4 is an enlarged cross-section.

The engine comprises the cylinder blocks A and B mounted upon the crank case C and spaced from each other. The blocks A and B have the plurality of cylinders A' and B' respectively, which have the water jackets A² and B² respectively. Slidably engaging the cylinders A' and B' are the pistons D which have the connecting rods E engaging

the cranks F of the crank shaft F', which is 55 rotatably mounted within the crank case C.

For controlling the inlet of the gaseous mixture to the cylinders the hollow rotary valves G and H are provided in the cylinder blocks A and B respectively at one side of 60 the cylinders and in the heads thereof. For controlling the exhaust from the cylinders the hollow rotary valves I and J are provided respectively in the cylinder blocks A and B at the opposite side of the cylinders 65 and in the heads thereof. These valves are suitably ported for correctly admitting the gases and permitting of the exhaust thereof. The inlet rotary valves G and H and also the exhaust rotary valves I and J extend inwardly between the cylinder blocks A and B and the inlet rotary valves communicate with each other respectively, whereby they form passage-ways extending the length of the engine.

For driving the rotary valves the spiral gear K is non-rotatably mounted upon the adjacent ends of the inlet rotary valves G and H and the spiral gear L is non-rotatably mounted upon the adjacent ends of the exhaust rotary valves I and J. Non-rotatably mounted upon the crank shaft F' and longitudinally centrally thereof is the spiral gear M having the teeth M' engaging the teeth N of the worm gear N' which is non-rotatably mounted upon the lower end of the shaft O. Non-rotatably mounted at the upper end of the shaft O are the worm gears P and Q for respectively engaging the spiral gears K and L. The shaft O extends intermediate the cylinder blocks A and B and is inclined with respect to the vertical axis of the cylinders in order to secure the proper driving relations. Also mounted within the crank case C is the spiral gear R 85 engaging the teeth N of the worm gear N' the spiral gear R being adapted to drive the pump or other accessories (not shown) of the engine.

An important feature of the invention resides in the arrangement of induction conduit, which is as follows: S is the induction conduit, to which the carburetor (not shown) is secured. This conduit is bifurcated and has the arms T and T' branching in opposite directions and passing through the water-jackets A² and B² respectively. At the opposite or outer ends of the engine are

the cylinder blocks A and B. The return-bent conduits U and U' are provided communicating with the arms T and T' and with the rotary inlet valves G and H respectively. 5 With this arrangement the gaseous mixture passing from the carburetor into the induction conduit is free to enter both arms of the conduit and to enter at opposite ends of both rotary valves so that regardless of the firing 10 arrangement of the cylinders of the engine substantially constant amounts of the gas are present in the rotary valves ready to enter the cylinders. The rotary valves being connected also permit of the passage of 15 the gaseous mixture from either arm of the induction conduit through its respective rotary valve into the other rotary valve, if necessary. The return-bent conduits at the opposite ends of the cylinder blocks are simple and furthermore effectively place the 20 arms of the induction conduit in communication with the rotary valves. The exhaust from the cylinders is provided for by a very similar arrangement of the exhaust conduit 25 V passing through the water-jacket and connected to the opposite ends of the rotary valve, or the exhaust rotary valves I and J respectively. This exhaust conduit also provides means for heating the cooling fluid enclosed within the water-jackets A² and B².

From the above description it will be readily seen that I have provided a simple and effective construction of engine in which the fluctuations of the gaseous mixture within 30 the passage, adapted to communicate with the cylinders is greatly lessened and furthermore the gaseous mixture passing into the engine cylinders is preheated. Also means is provided for accurately driving the rotary 35 valves from a single drive shaft.

In the usual engine construction a portion of the exhaust gases are drawn into the cylinders because the valves do not remain against their seats and because of the momentum of the exhaust gases. With my 40 construction, as shown particularly in Figure 1, the partition V' is provided between the exhaust rotary valves I and J so that the exhaust gases can not pass from the valve in one cylinder block to the valve in the other cylinder block.

An important feature of my invention, as shown in Figure 3, resides in the means for 45 variably controlling the inlet of the gaseous mixture to the engine cylinders. As shown, the modified construction has the same arrangement and combination of parts, as shown in Figure 1, with the additional means for variably controlling the inlet of the 50 gaseous mixture to the engine cylinders. This means comprises the rotatable inlet sleeves W surrounding both the inlet 55 rotary valves G and H and suitably ported to correspond with the ports into the engine cylinders. Connected to the sleeves W are

the levers W' which are adapted to be manually operated through connections (not shown). With this construction the admission of the gaseous mixture can be controlled simply by rotating the sleeves to vary the 70 time of opening and closing the ports so that a mixing valve can be used instead of a carburetor and its throttle valve. That is, the sizes of the ports are varied by the sleeves instead of varying the size of the passage to the induction conduit. 75

What I claim as my invention, is:

1. In an internal combustion engine, the combination with cylinder blocks, each comprising a plurality of cylinders and a rotary valve adapted to communicate with its respective cylinders, said valves communicating with each other, of a bifurcated induction conduit communicating with the opposite ends of said valves, and means intermediate said cylinder blocks for driving said rotary valves. 80

2. In an internal combustion engine, the combination with cylinder blocks, each comprising a plurality of cylinders, a rotary valve adapted to communicate with its respective cylinders and a water jacket for the cylinders, said valves communicating with each other, of a bifurcated induction conduit having the arms thereof passing through said water jackets to the opposite ends of said blocks, and return-bends at said ends for connecting said arms into said rotary valves. 85

3. In an internal combustion engine, the combination with cylinder blocks, each comprising a plurality of cylinders, a rotary valve for controlling the inlet to said cylinders, and a rotary valve for controlling the exhaust from said cylinders, said inlet and 100 exhaust rotary valves being respectively connected to each other intermediate said blocks, and spiral driving means for rotating said valves, extending between said blocks and between said rotary valves. 105

4. In an internal combustion engine, the combination with cylinder blocks, each comprising a plurality of cylinders, a rotary valve for controlling the inlet to said cylinders, and a rotary valve for controlling the 110 exhaust from said cylinders, said inlet and exhaust rotary valves being respectively connected to each other intermediate said cylinder blocks, spiral gears respectively mounted upon said inlet and exhaust rotary valves, 115 a driving shaft extending between said cylinder blocks and between said inlet and exhaust rotary valves, and worm gears upon said shaft for respectively engaging said spiral gears. 120

5. In an internal combustion engine, the combination with the crank shaft, of cylinder blocks each comprising a plurality of cylinders, pistons within said cylinders connected to said crank shaft, rotary valves 125

- upon opposite sides of said cylinders for respectively controlling the inlet and exhaust to and from said cylinders, said inlet and exhaust rotary valves of said blocks being respectively connected to each other intermediate said blocks, spiral gears upon said inlet and exhaust rotary valves, a shaft extending between said blocks and between said inlet and exhaust rotary valves and inclined with respect to the vertical axis of said cylinders, worm gears upon said shaft for respectively engaging said spiral gears, a spiral gear upon said crank shaft, and a worm gear at the lower end of said shaft and engaging said spiral gear upon the crank shaft.
6. In an internal combustion engine, the combination with cylinder blocks each comprising a plurality of cylinders of an exhaust rotary valve within each of said cylinder blocks, said valves being in substantial alignment with each other said valves being connected to each other, and a partition intermediate said valves for separating the interiors of said valves from each other.
7. In an internal combustion engine, the combination with cylinder blocks, of rotary valves controlling the inlet ports in said blocks, said valves being directly connected to each other intermediate said blocks and communicating with each other, and means intermediate said blocks and surrounding said valves for rotating the same.
8. In an internal combustion engine, the combination with cylinder blocks, of rotary valves for controlling the inlet ports in said blocks, said rotary valves being connected to each other intermediate said blocks, ported sleeve surrounding said rotary valves within said blocks, and means at the adjacent ends of said sleeves for rotating the same.
9. In an internal combustion engine, the combination with a series of cylinders, of a pair of exhaust rotary valves each adapted to communicate with a plurality of cylinders, said valves being in substantial alignment with and connected to each other, and a partition extending transversely of the axes of and intermediate said valves for separating the interiors thereof from each other.
10. In an internal combustion engine, the combination with a plurality of cylinders, of a plurality of intercommunicating rotary valves for said cylinders, said valves being in substantial alignment with and having adjacent ends connected to each other, a bifurcated induction conduit communicating with the opposite ends of said valves, and means intermediate said cylinders and surrounding said rotary valves for driving said rotary valves.
11. In an internal combustion engine, the combination with a plurality of cylinders, of a pair of rotary valves adapted to control said cylinders respectively, an adjustably rotatable sleeve surrounding each of said valves for varying the size of each cylinder inlet port, means arranged between said cylinders for rotating said valves, and means between said cylinders for adjustably rotating said sleeves.
12. In an internal combustion engine, the combination with a plurality of cylinders, of a passageway adapted to communicate with said cylinders, fittings at opposite ends of the engines provided with induction passageways communicating with said first-mentioned passageway, means terminating within the ends of the engine for controlling the communication with said first-mentioned passageway with the cylinders, and means intermediate a pair of cylinders for rotating said controlling means.
13. In a water jacketed internal combustion multi-cylinder engine, the combination with a rotary passageway adapted to communicate respectively with the cylinder, of a bifurcated induction conduit having the arms thereof passing through the jacket of the engine at one side thereof and leading to the opposite ends of the engine, means at the opposite ends of the engine for connecting said arms into said rotary passageway, and means intermediate a pair of cylinders and operatively connected to said rotary passageway to rotate the same.
- In testimony whereof I affix my signature.

FRANCIS E. FOULKE.
